UNITED STATES PATENT OFFICE.

GEORGE EDWARDS, OF BRUSSELS, ONTARIO, CANADA.

DITCHING-MACHINE.

1,113,318.

Specification of Letters Patent.

Patented Oct. 13, 1914.

Application filed June 21, 1913. Serial No. 774,986.

To all whom it may concern:

Be it known that I, GEORGE EDWARDS, of the town of Brussels, in the county of Huron, in the Province of Ontario, Canada, 5 have invented certain new and useful Improvements in Ditching-Machines, of which the following is the specification.

My invention relates to improvements in ditching machines and the object of the invention is to devise a simple means for excavating drain ditches so that the earth is conveyed out of the ditch and passed rearwardly of the machine back into the ditch over the tiles previously laid in the ditch 15 as it is formed and it consists essentially of a main truck frame supported on suitable wheels, a main driving shaft supported in suitable bearings and extending crosswise of the truck, upwardly extending arc-shaped guide-ways formed concentric with the center of the driving shaft, supplemental guide arms swung upon the driving shaft and having supplemental arc-shaped guide bars secured to one end thereof and 20 movable in the aforesaid arc-shaped guide-ways, an endless bucket conveyer supported by the opposite end of the supplemental guide bars in proximity to one end and connected at the other end to the lower end of 25 the supplemental arc-shaped guide bars, a cutting lever pivoted between the supplemental guide bars intermediately of its length, an arc-shaped cutting bar slidably held between the aforesaid supplemental 30 arc-shaped bars and connected to the corresponding end of the cutting bar lever, an operating crank supported in suitable journals carried by the supplemental guide bars, a link connecting the crank with the cutting 35 bar lever, means for driving the crank from the main shaft, cutting knives supported by the arc-shaped cutting bar at its lower end, a scoop carried by the bucket conveyer and designed to receive the earth cut by 40 the knives, means for adjusting the supplemental arc-shaped guide bars radially, means for driving the truck in unison to the operation of the cutting knives and a supplemental conveyer designed to convey 45 the earth from the main conveyer down into the ditch as hereinafter more particularly explained by the following specification.

Figure 1, is a general perspective view of 50 my device. Fig. 2, is a longitudinal section

through Fig. 1 showing my machine applied to the cutting of a ditch. Fig. 3, is a sectional detail of a portion of the driving mechanism. Fig. 4, is a sectional detail of the arc-shaped guiding bars and cutting bar 60 on line $x-y$ Fig. 2. Fig. 5, is a sectional view on line x^2-y^2 Fig. 2. Fig. 6, is a front elevation of the cutting bar adjusting mechanisms.

In the drawings like letters of reference 65 indicate corresponding parts in each figure.

A is the main truck frame comprising the outer timbers A' and A², cross connecting end timbers A³ and A⁴ and the longitudinal intermediate timbers A⁵ and A⁶. 70

B are the driving wheels supported on the axle B' and B² are the front or steering wheels supported on axles B³ swiveled on the ring bolt B⁴, the axle being swung on the ring bolt by any suitable mechanism which is not shown in the drawing as it forms no part of this invention. 75

C are bearings extending upwardly from the side bars A' and A² of the truck frame 80 intermediately of their length.

C' are bearings extending upwardly from the intermediate longitudinal bars A⁵ and A⁶.

D is the main driving shaft.

D' is a supplemental shaft journaled in 85 the timber A' and intermediate timber A⁵.

D² is a sprocket gear mounted on the shaft D'.

D³ is a sprocket gear mounted on the 90 main driving shaft D.

D⁴ is a sprocket chain connecting the sprocket wheels D² and D³ together.

D⁵ is a sprocket wheel also mounted on the shaft D' and D⁶ is a sprocket wheel connected to one of the driving wheels B. 95

D⁷ is a sprocket chain connecting the sprocket wheel D⁶ to the sprocket chain D⁵.

It will thus be seen that the main driving shaft D which is operated from any suitable source of power is adapted to actuate the wheel B through the sprocket wheel D⁶, sprocket chain D⁷, sprocket wheel D⁵ mounted on the shaft D', through the shaft D' to the sprocket wheel D² to the sprocket chain D⁴ and sprocket wheel D³ mounted on the main driving shaft. 100

E are arc-shaped guide bars extending upwardly from the intermediate longitudinal bars A⁵ and A⁶. The guide bars E are 105 concentric with the center of the main shaft 110

D and are provided with internal opposing guide-ways E'.

5 E² and E³ are supplemental guide bars swung in proximity to their lower ends on the main drive shaft D.

10 F are supplemental arc-shaped guide bars slidably held in the guide-ways E'. The supplemental arc-shaped guide bars F are connected to the supplemental guide bars E² and E³ at the ends thereof. The arc-shape guide bars F are connected together by cross plates F' and F².

15 F³ is an arc-shape cutting bar slidably supported between the bars F. The cutting bar F³ is provided with a notch F⁴ (see Fig. 2) across which extends a pin F⁵.

F⁶ is a cutting bar lever swung upon a cross bolt F⁷ extending through the supplemental cutting bars E³.

20 G are standard bearings extending upwardly from each of the guide bars E² and E³.

G' is a crank shaft journaled in the standards G and provided at one end with a 25 driving gear G².

G³ is a link connecting the crank shaft G' with the cutting bar lever F⁶.

30 H is a pinion mounted upon the main driving shaft D and meshing with the gear G².

H' is a main driving pulley mounted upon a main shaft D, the driving pulley H' being driven from any suitable source of power such as a gasoline engine mounted on the 35 frame of the truck.

I is an endless bucket conveyer secured to that portion of the guide bars E², and E³ projecting below the main shaft D. The lower end of the endless conveyer is connected by arc-shaped bars I' shown by dotted lines in Fig. 1 to the supplemental guide bars F.

40 I² is a scoop secured beneath the bucket conveyer in proximity to its lower end.

45 J is a pulley mounted upon the opposite end of the crank shaft G' and J' is a pulley mounted on the shaft J² of the bucket conveyer I.

J³ is a driving belt connecting the pulleys 50 J and J' together.

J⁵ are a series of cutting knives secured to the cutting bar F³.

K is a supplemental endless conveyer depending in an inclined direction from the 55 rear end of the truck frame A so as to convey the dirt down in as close proximity as possible to the drain tiles 2 which are arranged in the usual manner in the bottom of the drain cut 3. The supplemental conveyer K is driven from the main shaft D through the gear K' mounted upon the opposite end of the main shaft D and the gear K² mounted upon the stud shaft K³ and meshing with the gear K' and the pulley 60 K⁴ connected to the gear K², the pulley K⁴

being connected by a belt K⁶ to a pulley K⁷ mounted upon the upper shaft K⁷ of the supplemental conveyer.

Having described the principal parts involved in my invention I shall briefly describe the operation of the same.

As before described the pulley H' is driven from any suitable source of power which rotates the crank shaft G' through the gears G² and H. As the crank shaft 75 revolves it swings the cutting lever F⁶ on the bolt F⁷ reciprocating the opposite end of the lever through an arc and the cutting bar between the supplemental guide bars F. By the reciprocation of the cutting bar F³ 80 the cutting knives slice the earth in a substantially vertical direction. The loose earth as it falls to the bottom of the drain cut is gathered up by the scoop I² as the truck A is driven forwardly.

85 As the earth is collected in the scoop it is gathered by the buckets of the bucket conveyer and carried upwardly in an inclined direction and thrown on to the supplemental conveyer K which again conveys it into the drain cut filling it in and covering the tiles.

In order to regulate the depth of the cut I provide the following mechanism: L is a rack section formed on one of the arc-shape guide bars F. L' is a cross shaft journaled in 90 bearings L², and L³ is a pinion mounted on the shaft L' and meshing with the quadrant L. L⁴ is a hand wheel secured to the shaft L'. By throwing the wheel L⁴ the guide bars F may be raised or lowered as desired 100 carrying the cutting bar F³ with it and thereby regulating the depth of the cut made by the cutting knives.

From this description it will be seen that I have devised a very simple form of ditching machine which will operate rapidly to cut the ditch and convey the earth cut thereby to the rear of the machine so as to deposit it again in the ditch and over the tiles which have been arranged therein so 105 as to fill up the cut.

110 What I claim as my invention is:

1. A ditching machine comprising a truck frame and supporting wheels, arc-shaped guide-ways extending upwardly from the 115 supporting frame, an arc-shape cutting bar located between the guide-ways and slidably in a substantially circumferential direction, cutting knives supported thereby, a pivoted cutting bar lever connected at one end to the cutting bar, and means for reciprocating the opposite end of the lever, as and for the purpose specified.

120 2. A ditching machine comprising a truck frame and supporting wheels therefor, arc-shaped opposing guide-ways extending upwardly from the truck, an arc-shape cutting bar held between the arc-shape guide-ways, cutting knives supported by the bar, means for adjusting such bar vertically to regulate 125 130

the depth of the cut, a pivoted operating lever connected at one end to the cutting bar, and means for reciprocating the opposite end, as and for the purpose specified.

5 3. A ditching machine comprising a truck frame and supporting wheels therefor, opposing arc-shape guide-ways extending upwardly from the truck, supplemental arc-shape guide-ways supported in the aforesaid 10 arc-shape guide-ways, an arc-shape cutting bar slidably held between the supplemental guide-ways, means for adjusting the supplemental guide-ways vertically between the main arc-shape guide-ways, and means for 15 reciprocating the arc-shape cutting bars, as and for the purpose specified.

4. A ditching machine comprising a truck frame and supporting wheels therefor, opposing arc-shape guide-ways extending upwardly from the truck, supplemental arc-shape guide-ways supported in the aforesaid arc-shape guide-ways, an arc-shape cutting bar slidably held between the supplemental guide-ways, means for adjusting the supplemental guide-ways vertically between the main arc-shape guide-ways, a cutting lever 25 pivotedly supported in suitable bearings and connected at one end to the arc-shape cutting bar, and means at the opposite end for reciprocating the lever, as and for the purpose specified.

5. A ditching machine comprising a truck and supporting wheels therefor, arc-shape guide-ways extending upwardly from the truck, an arc-shape cutting bar supported 35 between the guide-ways, a cutting knife carried by the cutting bar, a pivoted operating lever connected at one end to the cutting bar, and means for reciprocating the opposite 40 site end of the lever.

6. A ditching machine comprising a truck frame and supporting wheels therefor, arc-shape guide-ways extending upwardly from the truck frame, supplemental arc-shape 45 guide bars supported in the aforesaid guide-ways, an arc-shaped cutting bar reciprocating between the supplemental guide bars, cutting knives connected to the arc-shaped cutting bar, conveying means for conveying the cut 50 dirt rearwardly and arc-shaped hangers connecting the lower end of the conveying means to the supplemental arc-shaped guide bars, as and for the purpose specified.

7. In a ditching machine, the combination 55 with a main supporting frame, of arc-shaped guide-ways extending upwardly from the frame, cutting means designed to travel in the arc-shaped guide-ways, conveying means swung intermediately of its length concentric with the arc-shaped guide ways, means 60

for actuating said cutting means and means located on the arc-shaped guide-ways for adjusting the throw of said cutting means.

8. A ditching machine comprising a truck frame and supporting wheels therefor, arc-shape guide-ways extending upwardly from the truck frame, supplemental arc-shape guide bars supported in the aforesaid guide bars, an arc-shape cutting bar reciprocating between the supplemental guide bars, cutting knives connected to the arc-shape cutting bar, an endless bucket conveyer, arc-shape hangers connecting the lower end of the bucket conveyer to the supplemental arc-shape guide bars and a collecting bucket 75 supported beneath the bucket conveyer in proximity to the cutting knives, as and for the purpose specified.

9. A ditching machine comprising a truck frame and supporting wheels therefor, arc-shape guide-ways extending upwardly from the truck frame, supplemental arc-shape guide bars supported in the aforesaid guide bars, an arc-shape cutting bar reciprocating between the supplemental guide bars, cutting knives connected to the arc-shape cutting bar, an endless bucket conveyer, arc-shape hangers connecting the lower end of the bucket conveyer to the supplemental arc-shape guide bars and a collecting bucket 90 supported beneath the bucket conveyer in proximity to the cutting knives.

10. A ditching machine comprising a truck frame and supporting wheels therefor, a main driving shaft journaled in bearings 95 on the truck frame and extending across the same, arc-shape guide-ways extending upwardly from the truck frame concentric with the center of the driving shaft, supplemental arc-shape guide bars held in the 100 opposing guide-ways, arms swung in proximity to one end thereof to the main driving shaft and connected at their opposite end to the arc-shape supplemental guide bars, an endless bucket conveyer secured to the opposite ends of the aforesaid arms, arc-shape hangers connecting the lower end of the bucket conveyer to the supplemental guide bars, an arc-shape cutting bar slidably held between the supplemental guide bars, a cutting bar lever pivoted intermediately of its 105 length between the connecting arms, a crank and link mechanism for operating the lever, and a notch connection between the opposite end of the lever and the cutting bar, as 110 and for the purpose specified.

GEORGE EDWARDS.
